UNITED STATES PATENT OFFICE.

EDUARD KRAEMER, OF COLOGNE, GERMANY.

AUTOMATIC GRAB.

1,030,191.

Specification of Letters Patent. Patented June 18, 1912.

Application filed October 17, 1911. Serial No. 655,239.

To all whom it may concern:

Be it known that I, EDUARD KRAEMER, a subject of the German Emperor, residing at Cologne-on-the-Rhine, Prussia, Germany, 5 have invented new and useful Improvements in Automatic Grabs; and I do hereby declare the following to be a full, clear, and exact description of the same.

This present invention relates to an arrangement in automatic grabs whose cups do not touch one another in the closed position and which enables the grab to be completely closed in a simple and effective manner.

15 Broadly stated the arrangement consists of two yokes suspended from the cups in such manner that, when the grab is closed, the slot left between the cups thereof will be covered by said yokes. On opening the 20 grab, the yokes will be moved laterally by a simple stop or the like.

The invention is illustrated in the accompanying drawings, wherein:

Figure 1.— is a front elevation of the 25 automatic grab in its closed position, Fig. 2.— is a similar view showing the grab in its open position and Fig. 3.— is a side elevation of same.

In these drawings, 1 represents the cups, 30 2 the yokes suspended at 3 from said cups so that they have the tendency to occupy vertical positions by gravity. The cups are provided with stop-pins 4, which move the yokes laterally when the grab is opened.

35 As shown in Fig. 2, the yokes do not at all hinder the operation of the cups as they may be freely moved rearwardly. As soon as the grab is being closed, the yokes follow their movements by gravity and finally

form a cover-plate for the lower and lateral 40 slots between the cups, when the grab is completely closed. The yokes are made of such width that the materials to be conveyed take their natural angle of slope in the space between the yokes and the cups. Instead of causing the yokes to be closed by 45 mere gravity, said yokes may be provided with pressure-springs 5 shown in the left parts of the views of the accompanying drawings.

Having fully described the nature of my invention, what I claim and desire to secure by Letters Patent is:—

1. In an automatic grab of the class described, the combination with the usual cups 55 arranged to leave an open slot between them in their closed position, of yokes suspended from said cups and made of such width that they form a cover-plate for said open slot when the grab is closed, substantially 60 as set forth.

2. In an automatic grab of the class described, the combination with the usual cups arranged to leave an open slot between them in their closed position, of yokes suspended 65 from said cups and capable of forming a cover-plate for said open slot when the grab is closed, and means for moving said yokes laterally when the grab is opened, substantially as set forth.

70 In testimony whereof, I have signed my name to this specification in the presence of two subscribing witnesses.

EDUARD KRAEMER.

Witnesses:
